United States Patent Office

Des. 178,945
Patented Oct. 16, 1956

178,945

MOBILE

Arnold F. Arnold, Port Jefferson, N. Y.

Application April 18, 1955, Serial No. 35,542

Term of patent 3½ years

(Cl. D29—1)

Fig. 1.

Fig. 2.

Fig. 3.

I claim:

The ornamental design for a mobile, as shown.
